CONTINUOUS STRIP PICKLING AND
CLEANING DEVICE

Frank J. Wood, Riverside, Ill., assignor to Goodman Manufacturing Company, Chicago, Ill., a corporation of Illinois

Application June 17, 1940, Serial No. 340,880

3 Claims. (Cl. 266—7)

This invention relates to improvements in continuous strip pickling and cleaning devices, and more particularly relates to improvements in the acid trough and tank construction of such a device.

Heretofore continuous pickling and cleaning systems have been provided with one more pickling and cleaning tank than is necessary to thoroughly pickle and clean the metal, so one pickling tank can be taken out of the pickling line at a time for cleaning or renewing the pickling fluid, in order to prevent inefficient cleaning of the metal due to the loss of one tank from the system or to prevent stopping of the entire line until the desired tank has been cleaned.

The principal objects of my invention are to remedy this by providing a pickling trough, through which the strip metal passes during the cleaning operation, and by providing a plurality of interconnected settling tanks into which the pickling fluid may drain as it is discharged from the pickling trough, and arranging said settling tanks so that fluid from one tank may be used for pickling while fluid in the other tank is settling or being cleaned.

Another object of my invention is to provide a plurality of pickling troughs in line, through which the strip metal passes during the cleaning operation, each of said troughs having a plurality of settling tanks connected together so fluid from either settling tank may be used for pickling, and connecting the settling tanks for one pickling trough with the settling tanks for the other pickling trough so fluid may be pumped from any of the settling tanks for one pickling trough and used in the other pickling trough, so as to permit the pickling fluid used for rough pickling to be used again in bright pickling, or vice versa.

Still another object of my invention is to provide a continuous pickling and cleaning device for strip metal including a pickling trough through which the strip metal passes during the cleaning operation, arranged so that pickling fluid will be discharged from its ends, and to provide a common sewer connected with the discharge ends of said pickling trough and leading to a plurality of separate storage and settling tanks disposed beneath said pickling trough and adapted to selectively supply pickling fluid thereto.

Other objects of my invention will appear from time to time as the following specification proceeds and with reference to the accompanying drawings wherein:

Figure 1 is a diagrammatic plan view of a pickling and cleaning line constructed in accordance with my invention;

Figure 2 is a diagrammatic view in side elevation of the pickling and cleaning line shown in Figure 1;

Figure 3 is an enlarged partial fragmentary plan view of one of the pickling troughs shown in Figures 1 and 2, with certain parts broken away and certain other parts shown in section;

Figure 4 is a partial longitudinal sectional view showing the discharge end of one of the pickling and cleaning troughs and also showing certain details of one of the settling tanks for said trough;

Figure 5 is a fragmentary transverse sectional view taken substantially along line 5—5 of Figure 4, but drawn to a reduced scale;

Figure 6 is an enlarged fragmentary transverse sectional view taken substantially along line 6—6 of Figure 4;

Figure 7 is an enlarged fragmentary sectional view taken substantially along line 7—7 of Figure 4; and

Figure 8 is a diagrammatic view illustrating the fluid circulation system.

In the drawings, the continuous strip pickling and cleaning device embodying my invention includes a coil supporting box 10 disposed at the entering end of the apparatus and forming a support for a coil of strip metal, permitting it to be unwound and passed through the cleaning apparatus by the usual opposed rollers. A leveler 12 consisting of a plurality of power driven leveling rolls 13, 13 engaging opposite sides of the metal, for leveling and breaking the scale on the metal before the cleaning operation, is provided in advance of said coil supporting box. A pickling trough 15 is provided in advance of said leveler. Squeegee and brushing and scrubbing rolls 16, 16 are provided at the discharge end of said pickling trough. Another pickling trough 17, similar to the pickling trough 15, is disposed in advance of said squeegee and brushing and scrubbing rolls. Squeegee and brushing and scrubbing rolls 19 are disposed in advance of the discharge end of said last mentioned pickling trough. From said squeegee and brushing and scrubbing rolls the metal may pass through a drier 21 to a coiler 23, which recoils the metal. Said coil supporting box, leveler, squeegee and brushing and scrubbing rolls, drier and coiler are only shown in an illustrative form since they are no part of the present invention except insofar as the appara-

tus of the present invention may be a part of an entire pickling system.

Referring now in particular to the details of the pickling troughs 15 and 17 and the settling tank construction for each of these troughs, said troughs are of a similar construction so like part numbers will be applied to like parts of each trough and the settling tanks therefor, and one only will herein be described in detail. Each pickling trough includes an elongated rectangular metal shell 25, herein shown as being supported on a framework including a plurality of spaced transversely extending I-beams 26, 26 with upright members 27, 27 extending upwardly along opposite sides of said shell.

The shell 25 is provided with a lining impervious to the effects of the acid in the pickling solution. Said lining is indicated generally by reference character 29 and may be a cement impervious to the effects of acid in the pickling solution, or may be acid resisting bricks set in sulphur cement, or any other suitable type of lining. Inner metal side walls 30, 30 are provided for said trough. Said side walls are mounted on and extend along the inner sides of the lining of said shell and may be of a sectional construction to permit ready cleaning of the trough. Said side walls may be constructed from any usual type of acid resisting metal but are preferably constructed from a cast iron having a high silicon content so as to resist the effects of the acid of the pickling solution, and also to resist the abrasive effects of the edges of the metal as it passes through said trough. The entire trough is covered by a sectional cover 32. A plurality of spaced apart blocks or runners 33, 33 are provided along the bottom of the pickling trough to form a surface along which the metal may slide during pickling. As herein shown, said runners are mounted on transversely extending shafts 34, 34 mounted at their ends in the side walls 30, 30 and spaced apart by spacing members 35, 35 (see Figure 7). Said blocks may be made from any suitable material which will not scratch the surface of the metal as it passes thereover, such as glass or various forms of smooth plastics. One form of plastic material which may be used is that material which is commercially known as "Haveg."

Fluid enters the pickling trough from the sides thereof beneath the top of the runners 33, 33 through spaced apart pipes 36, 36, the ends of which extend into transversely recessed portions 37, 37, formed in the bottom of said trough. Said pipes open into said recessed portions so as to circulate pickling fluid transversely of said trough. The volume of fluid coming through said pipes is sufficient to permit the pickling fluid to discharge through the ends of said trough and through a discharge opening 38 in the discharge end thereof and still maintain the level of the pickling fluid above the tops of the runners 33, 33 so both surfaces of the metal will be adequately pickled. Said pipes are connected with longitudinally extending pipes or conduits 39, 39 extending along said trough and herein shown as being disposed thereabove. Said pipes are herein shown as being in longitudinal alignment with each other and one of said pipes extends along one portion of one trough, for supplying pickling fluid thereto, while the other pipe extends along the other portion of the same trough. Fluid is supplied to said longitudinally extending conduits by means of a pair of spaced apart fluid pressure pumps 41, 41 each one of which pumps

is adapted to supply fluid to a pipe 39. Said pumps may be centrifugal pumps of a construction well known to those skilled in the art and are connected with said longitudinally extending pipes by means of pipes 42, 42.

A plurality of settling tanks 44, 44 is provided beneath each pickling trough and a pump 41 is provided for each settling tank. As herein shown, two of such tanks are provided for each pickling trough but a greater number of tanks may be provided if desired. Said settling tanks may be of any form of acid resisting construction, but are herein shown as being made from a suitable acid resisting material similar to the material used in the construction of the pickling troughs 15 and 17. A pipe 45 is provided to connect said settling tanks together. A pipe 46 connects the pumps 41, 41 together and a pipe 47 connects the pipe 45 with the pipe 46. A pair of valves 49, 49 is provided in the pipe 45 on each side of the pipe 47 to shut off either settling tank 44 from either of the pumps 41, 41. A valve 50 is provided in each pipe 42 to shut off the supply of fluid from said pipe and its connected pipe 39 when desired. Thus pickling fluid may be pumped from either settling tank by either or both pumps 41, 41 and circulated through its connected pipe 39 and the associated nozzles 36, 36.

A connection is provided between the pressure sides of the pumps 41, 41 for each set of settling tanks for the pickling troughs 15 and 17, to connect the settling tanks for the pickling trough 15 with the settling tanks for the pickling trough 17, so pickling fluid from either one of the first set of settling tanks 44, 44 may be used for pickling in the second pickling trough, and pickling fluid from either one of the second set of settling tanks may be used in the first pickling trough if desired. Said connection includes a pipe 51 having connection with the pressure sides of the pumps 41, 41, and pipes 52, 52 leading from said pipe to the desired settling tank 44 (see Figures 1, 3 and 8). A valve 54 is provided in each pipe 52, to control the flow of pickling fluid into the desired settling tank. Valves 55, 55 are provided in said pipe adjacent each pump 41 to control the flow of pickling fluid into said pipe from said pumps. Fluid may thus be taken from any settling tank 44 and circulated through the system or may be emptied from any one tank and put into any other tank or tanks by means of the pumps 41, 41.

Waste pickling fluid is conducted to the desired settling tank 44 for each pickling trough, by means of sewers 53, 53. One of said sewers extends along one side of each pickling trough and across opposite ends thereof, and is arranged to collect pickling fluid flowing out of the ends of said trough and the drain 38, and to conduct said fluid to the desired settling tank. The sewer 53 is provided with openings or drains 56, 56. Each of said drains leads to one of the settling tanks 44. Said drains may be closed by a valve of any suitable construction or by means of a stopper. As herein shown, a stopper 57 is provided to close said opening. Access to said stopper may be had through covers 58, 58 for said sewer, and said stoppers may be pulled by means of a rod or chain connected thereto (not shown).

It may be seen from the foregoing that a new and improved arrangement of aligned pickling troughs and settling tanks has been provided which is so arranged that pickling fluid in one tank may be used as pickling fluid in the other

tank settles, or while the other tank is being cleaned, and that pickling fluid in any settling tank may be used in any desired pickling trough, thus avoiding delays which might be caused by shutting down the system for cleaning the tanks.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a continuous strip pickling and cleaning device, a pair of aligned pickling troughs, through which a strip of metal is adapted to pass during the pickling operation, a plurality of settling tanks arranged beneath each of said pickling troughs, fluid pipes connecting said tanks together, valves in said pipes arranged to shut off the flow of fluid from any one of said tanks to any other of said tanks, other fluid pipes connecting said tanks with said pickling troughs, valves in said pipes arranged to shut off the flow of fluid from any one of said tanks to any one of said pickling troughs, pumps for circulating fluid through said pipes from any one or more of said tanks to any other of said tanks and from any one or more of said tanks to any of said pickling troughs, a separate sewer extending along the ends and one side of each pickling trough for collecting the fluid discharged from its associated trough, connections between each sewer and the settling tanks associated with said trough, selectively operable to permit fluid to flow from said sewer to any one of its associated tanks.

2. In a continuous strip pickling and cleaning device, a pair of aligned pickling troughs through which a strip of metal is adapted to pass during the pickling operation, and means whereby pickling fluid in one trough may be used in the other trough and whereby pickling fluid in either of said troughs may be changed without stopping

the pickling operation including a plurality of settling tanks arranged beneath each of said pickling troughs and adapted to receive fluid discharged therefrom, fluid passageways connecting all of said tanks together, valves in said passageways arranged to control the flow of fluid from any one of said tanks to any other of said tanks, other fluid passageways connecting said tanks with said pickling troughs, valves in said passageways arranged to control the flow of fluid from any one of said tanks to any one of said pickling troughs, and a pump associated with each pickling trough, said pumps being located in said last mentioned passageways, for circulating fluid from said tanks to said troughs and between any one of said tanks.

3. In a continuous strip pickling and cleaning device, a pair of aligned pickling troughs through which a strip of metal is adapted to pass during the pickling operation, a separate sewer for each of said troughs, said sewers extending along and across the forward and rear ends of said troughs, for collecting pickling fluid flowing from the ends thereof, and means whereby pickling fluid in one trough may be used in the other and whereby pickling fluid in either of said troughs may be changed without stopping the pickling operation including a plurality of settling tanks arranged beneath each of said pickling troughs, fluid passageways arranged to selectively connect each sewer with the settling tanks beneath its associated pickling trough, fluid passageways connecting all of said tanks together, other fluid passageways connecting said tanks with said pickling troughs, valves in said passageways arranged to shut off the flow of fluid from any one of said tanks to any other of said tanks, and from any one of said tanks to any one of said troughs, a pump associated with each pickling trough, said pumps being located in said passageways leading from said tanks to said troughs, for circulating fluid between any one or more of said tanks and from any one or more of said tanks to any one of said pickling troughs.

FRANK J. WOOD.
